STOCKING

Joseph J. Keichel, Lehighton, Pa.

Application April 22, 1953, Serial No. 24,618

Term of patent 14 years

(Cl. D47—7)

To all whom it may concern:

Be it known that I, Joseph J. Keichel, a citizen of the United States of America, residing at Lehighton, Pennsylvania, have invented a new, original, and ornamental Design for a Stocking, of which the following is a specification, reference being had to the accompanying drawing, forming a part hereof.

The figure is an elevational view of the back of a stocking embodying my new design. The left portion of the figure extends upward from the top of the right portion of the figure. The front of the stocking is conventional.

I claim:

The ornamental design for a stocking, as shown and described.

JOSEPH J. KEICHEL.
